UNITED STATES PATENT OFFICE.

LAWRENCE GRIFFITH, OF YONKERS, NEW YORK, ASSIGNOR, BY MESNE ASSIGNMENTS, TO FEDERAL SIGNAL COMPANY, A CORPORATION OF NEW YORK.

SAFETY DEVICE FOR RAILWAY SWITCH AND SIGNAL APPARATUS.

No. 906,492.

Specification of Letters Patent.

Patented Dec. 8, 1908.

Original application filed November 5, 1904, Serial No. 231,514. Divided and this application filed February 20, 1906. Serial No. 302,029.

To all whom it may concern:

Be it known that I, LAWRENCE GRIFFITH, a citizen of the United States of America, residing in the city of Yonkers, county of 5 Westchester, and State of New York, have invented certain new and useful Improvements in Safety Devices for Railway Switch and Signal Apparatus, of which the following is a specification, reference being had to 10 the accompanying drawing.

This application is a divisional of my application #231,514, filed November 5, 1904.

My invention relates to railway switch and signal apparatus and its object is to provide 15 safety devices for both the indicator and the motor of such apparatus.

To these ends my invention consists broadly of means whereby, at certain times, the indicator may be prevented from acting 20 though the apparatus in other respects would be adapted to operate it.

Reference may be made to United States Letters Patent #724,180 and 776,238 granted to me respectively March 31, 1903 and 25 November 29, 1904.

In order that my invention may be clearly understood, I shall first describe in detail the manner in which I carry the same into practice, and then point out the novel features of the invention in the claim, reference being had to the accompanying drawing forming part of this specification.

The motion-plate A is operated pneumatically or by fluid under pressure, and the indicator 1 cooperates with operator's quadrant 2, though without departing from my invention, an operator's stroke-completing-bar, well known in the art, may be substituted for the quadrant. The piston 5 of 40 pneumatic motor W is operatively connected with motion-plate A. Pipe 7 supplies power from the valve X to operate piston 5 in one direction, and pipe 6 from valve Y to operate said piston in the other direction in the 45 usual way. Said valves X and Y are counterparts of each other, each having three ports. Ports 8 lead to the supply of compressed air or other fluid under pressure. Ports 10 lead to the atmosphere or exhaust. 50 Ports 9 lead to opposite sides of piston 5 of motor W. The valves X and Y are provided with pistons 11 adapted normally to

close supply ports 8 and open exhaust ports 10. Springs 12 normally hold said pistons in the position just above described. Co- 55 operating with said pistons 11 are magnets X' and Y', so that when id magnets are energized, pistons 11 will close exhaust ports 10 and open supply ports 8.

Upon the movement of the operator's 60 quadrant 2, bridge 14 will be brought into contact with springs 15 and 16, and valve X will be opened to admit compressed air by pipe 7 to motor W, as follows: wire 17, 65 relay 91, wire 18, contact springs 15 and 16, bridge 14, wire 19, contact springs 20 and 21, bridge 22, wire 23, magnet X', wire 24 to battery, so that armature X² of magnet X' will be raised, and, by energy supplied through valve X and pipe 7, piston 5 will 70 be moved and will carry with it motion-plate A and switch or controller M, thereby breaking connection between contact springs 21 and 20 and making connection between contact springs 25 and 26 by bridge 27; and 75 breaking contact between springs 28 and 29 by bridge 30 and making contact between springs 31 and 32 by said bridge 30. In this position, roller 33 will abut against shoulder 34 of the slot in the quadrant 2, and said 80 roller 33 will be raised by the action of indicator 1, which is energized as follows: wires 17, 35, 36, 37, solenoid or indicator 1, wire 38, contact springs 39 and 40, bridge 41, wire 42, contact springs 31 and 32, bridge 85 30, wire 98 to ground or battery. It will be understood that stops 51 and 51' operate to move bridge 41 during a portion only of the stroke of rod 52, which rod is mechanically 90 connected with quadrant 2 and moves with it carrying bridge 14. The said relay 91, being connected in series with the circuits of magnets X' and Y', as above described, is energized whenever current is on the circuit of either of said magnets X' and Y', 95 and it will be understood that when said relay 91 is energized the circuit of solenoid 1 will be broken between wires 36 and 37. I sometimes provide relay 91 with additional windings of higher resistance than that connected with wires 17 and 18, and connect such higher resistance by wires 44 and 45 in parallel with the circuits of magnets X' and Y' and in parallel with the low resist- 100

ance winding. In such case should an abnormally large current be sent through the operating circuit containing the lower winding causing the blowing out of fuse P, the 5 relay 91 would still act to hold open the circuit of solenoid 1 by the action of the upper winding, but normally the upper winding merely aids the lower winding in doing its work. It will be seen, therefore, that by the 10 action of relay 91 the electric connection of solenoid 1 will be broken when there is energy on the circuits of either of the magnets X' or Y'.

Of course, I do not limit myself to either 15 a series or a parallel electrical connection, nor to a return to battery by metallic circuit as distinguished from grounding.

What I claim and desire to secure by Letters Patent is:

In apparatus for operating switches, signals, and the like, comprising an electric indicator and a motor for the motion-plate or device to be moved, electric means separate from the indicator for preventing the action of the indicator while there is energy supplied to said motor.

In testimony whereof, I have hereunto set my hand this nineteenth day of February, 1906.

LAWRENCE GRIFFITH.

In presence of—

H. V. N. PHILIP,
J. F. BOUDREAU.
